(57) **CLAIM**

The ornamental design for an information display for a vehicle with a graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a first transitional image of an information display for vehicle with graphical user interface showing a first embodiment of our new design;

FIG. 2 is a second transitional image of the information display for vehicle with graphical user interface according to the first embodiment;

FIG. 3 is a third transitional image of the information display for vehicle with graphical user interface according to the first embodiment;

FIG. 4 is a fourth transitional image of the information display for vehicle with graphical user interface according to the first embodiment;

FIG. 5 is a first transitional image of information display for vehicle with graphical user interface showing a second embodiment of our new design;

FIG. 6 is a second transitional image of the information display for vehicle with graphical user interface according to the second embodiment;

FIG. 7 is a third transitional image of the information display for vehicle with graphical user interface according to the second embodiment; and,

FIG. 8 is a fourth transitional image of the information display for vehicle with graphical user interface according to the second embodiment.

The outer broken line illustrates the information display for vehicle. The remaining broken lines illustrate portions of the graphical user interface. The alternate long and short dash

(Continued)

line illustrates the boundary of the claimed design. Neither the broken lines nor the dash line form part of the claimed design.

The appearance of the transitional image sequentially transitions between the images shown in FIGS. 1-4. The appearance of the transitional image sequentially transitions between the images shown in FIGS. 5-8. The process or period in which one image transitions to another image forms no part of the claimed design.
